UNITED STATES PATENT OFFICE.

MAXIME MASSON, OF SCHUMACHER, ONTARIO, CANADA.

ROTARY ENGINE.

1,412,190.

Specification of Letters Patent. Patented Apr. 11, 1922.

Application filed January 22, 1921. Serial No. 439,325.

To all whom it may concern:

Be it known that I, MAXIME MASSON, a subject of the King of Great Britain, a resident of Schumacher, Province of Ontario, 5 Dominion of Canada, have invented certain new and useful Improvements in Rotary Engines, of which the following is a specification.

This invention relates to improvements in 10 rotary engines, and the object of the invention are to provide an engine that can be reversed, to provide an engine of simple construction and in which the working parts are not liable to go out of repair, to increase the 15 efficiency of the engine, and generally to adapt the several parts to better perform the functions required of them.

With the above and other objects in view, the invention consist essentially of the improved construction particularly described and set forth in the following specification illustrated in the accompanying drawings forming part of the same, and set forth in the appended claims.

25 In the drawings:

Figure 1 is a perspective view of the improved rotary engine.

Figure 2 is a longitudinal section through the engine.

30 Figure 3 is an end view of the engine.

Figure 4 is a cross section taken on the line 4—4 of Figure 2.

Figure 5 is a cross section taken on the line 5—5 of Figure 2.

35 Figure 6 is a perspective view of the rotor.

Figure 7 is a sectional detail taken on the line 7—7 of Figure 4.

Figure 8 is a sectional detail taken on the 40 line 8—8 of Figure 7.

Like characters of reference refer to corresponding parts in the several figures.

Referring to the drawings; A represents the improved rotary engine comprising a 45 casing 10 through which passes the shaft 11, one end of which is overhung and provided with a belt pulley 12.

This engine is designed to be reversible and to this end I provide a pair of inlet 50 steam conduits 13 and 14 respectively through which steam is delivered to impinge on the vane discs. Exhaust passageways 15 are provided in the casing and are formed with exhaust conduits 16 at the bottom of 55 the casing.

On the shaft 11 and towards the centre

thereof, a disc 17 is secured and on the opposite lateral faces of the said disc, discs 18 are keyed on the shaft, the last said discs being provided with peripheral notches 19.

60 Between each pair of notched discs 17 and 18 are located serrated vaned discs 20 and 21 while adjacent to the last said discs 18, discs 17 are secured on the shaft, and end discs 22 are placed on the shaft to embrace the said discs already positioned in the shaft.

65 Piston rings 23 are mounted on the disc 17 and form a steam connection between the said discs and the inner periphery of the casing 10.

70 Bolts 24 extend through the enlarged disc assembly to secure the several discs together to form a rotor, as shown in Figure 6. The serrated vaned discs 20 and 21 are constructed with their serrations oppositely disposed as shown in Figures 4 and 5, so that such discs will rotate the shaft 11 in predetermined but opposite directions, for instance, the discs 20 will when steam impacts on the vanes thereof, rotate the rotor in a clockwise direction, and the disc 21 will when steam impacts on the vanes thereof, rotate the rotor in an anti-clockwise direction.

75 The serrated disc 20 and its adjacent peripherally notched discs 18 form one unit, and vanes 25 are inserted in the notches 19 in the discs 18 and will engage with the flattened face of the serrations of the disc 20, and the vanes 25 are normally spring-pressed outwardly by springs 26 as clearly shown in Figure 7. The serrated disc 21 and the adjacent peripherally notched discs 18 form a second unit, and vanes 25 are mounted thereon and are normally spring-pressed outwardly by the springs 36.

80 When this rotary engine is in use and it is desired to rotate the same in a clockwise direction steam is admitted through the inlet conduit 14 and impinges on the vanes 25 and causes the serrated disc 20 to be rotated.

85 After the steam imparts on the vanes 25 and motion has been transmitted to the rotor, the steam is exhausted through the passage 15 to the exhaust conduit 16.

90 During this operation steam is not admitted to the conduit 13.

95 When it is found desirable to reverse the engine, steam is cut off from the inlet conduit 14 and steam is admitted to the conduit 13, so that the steam impacts with the vanes 25 of the serrated disc 21 and transmits ro-

tary motion to the rotor and in the anti-clockwise direction.

After the steam has impacted on the vanes 25 and started rotation of the rotor, 5 the steam will be exhausted through the passageway 15 to the exhaust conduit 16.

From this description it will be seen that I have invented a reversing rotary engine which can be used for stationary purposes 10 and in which the several parts are readily accessible for inspection and repair.

As many changes could be made in the above construction and many widely different embodiments of my invention within the 15 scope of the claims constructed without departing from the spirit or scope thereof, it is intended that all matter contained in the accompanying specification and drawings shall be interpreted as illustrative and not in a 20 limiting sense.

What I claim as my invention is:—

1. A reversible rotary engine comprising a casing, a shaft journalled in the casing, a pair of oppositely disposed serrated vaned discs, pairs of notched discs on opposite sides of the serrated discs, outwardly spring 25 pressed vanes fitting in the notches of the second said discs, a pair of discs adjacent the

outer notched discs, packing rings engaging the periphery of the last said discs, a pair of 30 larger discs adjacent the last said discs, and means for securing all the discs in assembled position.

2. A reversible rotary engine comprising a casing, a shaft journalled in the casing, 35 a pair of oppositely disposed serrated vaned discs, pairs of notched discs on opposite sides of the serrated discs, vanes formed with two lateral extensions designed to engage the notches, the body of the vanes being adapted to bear against the face of the serrations, means on the serrated discs to exert outward pressure against the vanes, a pair of discs adjacent to the outer notched discs, packing rings engaging the periphery 40 of the last said discs, a pair of larger discs adjacent to the last said discs, and means for securing all the discs in assembled position.

In witness whereof I have hereunto set my 50 hand in the presence of two witnesses.

MAXIME MASSON.
